UNITED STATES PATENT OFFICE.

CLARENCE P. CROWELL, OF ROCHESTER, NEW YORK, ASSIGNOR TO ROCHESTER GERMICIDE COMPANY INC., OF ROCHESTER, NEW YORK, A CORPORATION OF NEW YORK.

LIQUID-DISPENSING APPARATUS.

Application filed August 28, 1925. Serial No. 53,057.

My present invention relates to liquid dispensing apparatus and has for its object to provide more particularly an improved device for dispensing liquid soaps and the like. 5 A further object of the invention is to provide a dispensing device of this type which is simple in construction, economical to manufacture and efficient in operation. To these and other ends the invention resides in certain improvements and combinations of parts all as will be hereinafter more fully described, the novel features being pointed out in the claims at the end of the specification.

15 In the drawings:

Figure 1 is a side elevation embodying the invention;

Figure 2 is a longitudinal sectional elevation through the valve casing showing the 20 valve in normal closed position;

Figure 3 is a similar view with the valve shown in open position;

Figure 4 is a transverse sectional elevation taken on line 4^a—4^a of Figure 3 and

25 Figure 5 is a transverse sectional elevation taken on line 5^a—5^a of Figure 2.

Similar reference numerals throughout the several views indicate the same parts.

The present invention is designed, particularly for dispensing liquid soap in connection with lavatories having one or more wash bowls and is preferably adapted to project horizontally over the bowls or basins and to discharge downwardly into one hand 35 of the user upon operation of a control valve by the other hand.

The valve is indicated generally at 10 and its rear end is preferably screwed upon the outer end of a relatively short horizontally 40 disposed pipe 11 connected with a liquid supply reservoir 12 supported by any suitable means not shown. It will be understood that a number of the valves may be connected with the same reservoir if desired 45 through the use of the necessary connections including the short pipes 11 projected one over each bowl. The valve casing 13 is provided with inner and outer chambers 14 and 15, respectively, at the opposite sides 50 of an intermediate chamber 16 having a larger cross-sectional area than either of the opposing chambers. A cap or closure 17 is screwed upon the other end of the casing 13 and is provided with a downwardly project-

ing nozzle 18 in constant communication 55 with a recess 19 which is adapted to communicate with the valve chamber 15 in which is normally disposed a suitable valve 20. The valve is provided with an operating stem 21 having a detachable disc shaped 60 handle 22 thereon. A liquid tight joint is afforded around the stem by suitable packing 23 which is secured within the cap by a nut 24 forming a stop to limit the inward movement of the valve by engaging the 65 handle 22 as shown in Figure 3. The cap is provided preferably with a detachable valve seat 25 in the form of a gasket to receive the annular projecting portion 26 of the valve 70 as shown in Figure 2 whereby to more effectively prevent leaking of the valve. The valve is preferably made to closely fit the bore of the casing except the enlarged chamber 16 which forms a pocket in which the liquid is trapped when the valve is moved to 75 the position shown in Figure 3. When the valve is released from this position, it is automatically returned by a spring 27 whereby a predetermined quantity of the 80 liquid is ejected through the nozzle 18 as will be understood. The liquid is therefore discharged upon the return stroke of the valve rather than during advancement thereof.

The front end of the spring is disposed 85 within the recessed portion 28 of the valve while its rear end is seated upon a transverse wall 29 of the casing having fluid passages 30 therethrough, said wall carrying a forwardly projecting stem 31 extending into the spring to prevent displacement thereof. 90

A gradual closing of the chamber 14 is effected upon inner movement of the valve from the position shown in Figure 2. In moving the valve to the position shown in Figure 3 a predetermined quantity of liquid 95 is trapped in the chamber 16, a certain portion of which will escape into chamber 15 when the valve is moved therefrom, and this liquid will be forced through the nozzle 18 by the valve on return of the same to normal position. By providing the valve with laterally extending openings 32 its operation is made easier and smoother. Furthermore upon return of the valve from the position shown in Figure 3 said openings permit the 100 liquid to flow therethrough from the chamber 14 into the chamber 16 to insure rapid filling of the latter in advance of each in-

ward stroke of the valve whereby better results are afforded under the rapid action to which the valve is subjected in use.

The present device is one which is simple in construction, convenient to operate and which will effectively discharge a predetermined quantity of liquid downwardly into the hand at each return stroke of the valve. It is easy to keep in repair and the parts are readily accessible requiring only the removal of the cap 17.

I claim as my invention:

1. A liquid dispensing apparatus comprising a casing having inner and outer spaced valve chambers of equal bore and an intermediate chamber therebetween of greater cross-sectional area than either of said valve chambers, a valve normally closing the outer chamber and being movable through the intermediate chamber to close the inner chamber, said valve being so constructed that subsequent to entering the inner chamber it will permit the latter to remain in communication with the intermediate chamber for a predetermined period during inward movement of the valve, and means for returning said valve to normal position.
2. A liquid dispensing apparatus comprising a casing having inner and outer spaced chambers and an intermediate chamber therebetween of larger cross-sectional area than said outer chamber, a single valve normally closing said outer chamber and movable through the intermediate chamber into the inner chamber and being constructed to gradually cut off communication between the latter and the intermediate chamber when moving from the outer chamber, and means for returning said valve to normal position.
3. In a liquid dispensing apparatus in combination, a reservoir, a horizontally disposed casing connected therewith and having

a bore forming inner and outer spaced chambers and a liquid receiving chamber interposed therebetween of a larger cross sectional area than either of said spaced chambers, said receiving chamber and said inner chamber being normally in communication with the reservoir, a single valve corresponding in diameter to said bore and normally disposed in the outer chamber said outer chamber having a downwardly extending discharge passage, means for moving the valve through the liquid receiving chamber into the inner chamber to cut off communication between the receiving chamber and the reservoir and to place the other chamber in communication with the receiving chamber and means within the casing for automatically returning the valve to the outer chamber when released.

4. In a liquid dispensing apparatus in combination, a reservoir, a casing connected therewith and having inner and outer spaced valve chambers and a liquid receiving chamber interposed therebetween of a larger cross sectional area than either of the valve chambers said receiving chamber and said inner chamber being normally in communication with the reservoir and said outer chamber having a downwardly extending discharge passage, a hollow piston valve normally held within the outer chamber having its rear end projecting into the receiving chamber and provided with laterally extending passages whereby communication is gradually cut off between the inner and receiving chambers during inward movement of the valve, means for moving the valve from the outer to the inner chamber and means for automatically returning the valve to the outer chamber when released to force the liquid through said discharge passage.

CLARENCE P. CROWELL.
